US00D961168S

(12) **United States Design Patent** (10) **Patent No.:** **US D961,168 S**
(45) **Date of Patent:** **** Aug. 16, 2022**

(54) **PROTECTIVE SHIELD**

(71) Applicant: **DEXERIALS CORPORATION**,
Tokyo (JP)

(72) Inventor: **Shinya Suzuki**, Tokyo (JP)

(73) Assignee: **DEXERIALS CORPORATION**,
Tokyo (JP)

(**) Term: **15 Years**

(21) Appl. No.: **29/760,197**

(22) Filed: **Nov. 30, 2020**

(30) **Foreign Application Priority Data**

Jun. 24, 2020 (JP) ..... 2020-012658 D

(51) LOC (13) Cl. **02-99**

(52) U.S. Cl.

USPC **D29/122**

(57) **CLAIM**

The ornamental design for a protective shield, as shown and described.

DESCRIPTION

FIG. 1 is a front view of a protective shield showing my new design;

FIG. 2 is a back view thereof;

FIG. 3 is a left side view thereof;

FIG. 4 is a right side view thereof;

FIG. 5 is a plan view thereof;

FIG. 6 is a bottom view thereof; and

FIG. 7 is a perspective view thereof; and,

FIG. 8 is a perspective view showing a use state thereof. The broken lines shown are included for the purpose of illustrating portions of the protective shield and form no part of the claimed design. The dot-dash-dot lines indicate the boundary of the claim. The entire design is transparent.

1 Claim, 8 Drawing Sheets
